UNITED STATES PATENT OFFICE.

FRED H. BARNEY, OF TULSA, OKLAHOMA.

PUMP-ROD OR PITMAN CONNECTION.

1,243,031.

Specification of Letters Patent. Patented Oct. 16, 1917.

Application filed January 5, 1917. Serial No 140,838.

To all whom it may concern:

Be it known that I, FRED H. BARNEY, a citizen of the United States, residing at Tulsa, in the county of Tulsa and State of Oklahoma, have invented certain new and useful Improvements in Pump-Rod or Pitman Connections, of which the following is a specification.

This invention relates to pitman connections, and particularly to such connections as are employed on pump rods, although its use is not limited to such purposes, but may be employed wherever such connections will be found useful.

15 The object of the invention is to provide simple, cheap and strong connections designed to be used between the pump rod and the eccentric strap or crank of the driving power and is made of few parts and 20 may be readily renewed with slight labor and expense should breakage occur at any time without causing extended stoppage of the pumping operation.

With this object in view, the invention 25 consists of the construction, combination, and arrangement of parts, hereinafter described, pointed out in the claims, and illustrated in the accompanying drawings, in which—

30 Figure 1 is a side view of the improved connection secured on the end of a pump rod.

Fig. 2 is a view seen at right angles to Fig. 1 with portions of the connection 35 broken away.

Fig. 3 is an end view of the connection with the pump rod shown in section.

In the drawings, 10 indicates the pump rod or pitman, on the upper end of which is 40 attached a bushing 11 formed of two like parts 12 and 13, said parts having a semi-cylindrical groove extending from end to end to bear upon and embrace the rod 10.

The flat contact sides of said bushing members 12 and 13 are provided with outwardly 45 projecting flanges 14 that bear upon each other and serve to maintain the parts in proper position with relation to each other. The outer faces of each bushing part 12 and 50 13 is flat as at 15, such faces being parallel to each other and to the axis of the rod 10 and form seats for the lower ends of two plates 16 and 17, which plates are fastened to the coupling 11 by a bolt 18 passing 55 therethrough and through the bushing as

shown and being secured by means of a lock nut 19 on its opposite end.

The plates 17 at the upper edge of the bushing 11 are inclined outwardly and away from each other for a short distance, 60 as shown at 20, and then continue upwardly again parallel to each other and to the axis of the rod for a suitable distance forming two upwardly extending terminal members 21 that are connected by a bolt 22 with the 65 eccentric strap or crank of the motive power mechanism.

Pitman connections in present use are generally formed by welding the plates 16, 17 together and then drawing them out to bring 70 them to proper size for attachment to a bushing on the upper end of the pump rod and such constructions have a tendency to break at the welded portion, thus necessitating stoppage and expenditure of considerable time for repairs. In the present device plates 14 are exactly alike and screwed to opposite sides of the bushing 11 by means of a single bolt which can be quickly removed and a new plate as quickly attached 80 when through accident it becomes necessary to replace one of them. The connection is strong and simpler than the connections now in use and will give better satisfaction 85 and cause less delay than the present connections.

What I claim is:

1. A pitman connection comprising a pitman, a two-part bushing having flat sides and adapted to surround the pitman, two 90 similar spaced plates each having an inclined portion intermediate its ends to vary the width between opposite ends, the ends of said plates which are closer together being adapted to bear upon the flat sides of said bushing, a bolt passing through said plate ends, the bushing and the pitman, and means at the opposite ends of the plate for engaging a crank or eccentric operating mechanism.

2. In a pitman connection the combination with a bushing on the upper end of the pump rod or pitman, a plate on each of two opposite sides of said bushing rigidly bolted thereto, said plates spreading laterally above said bushing for a limited distance and then continuing to their extremities in parallel relation, and means for connecting the upper ends of said plates to a crank mechanism.

3. In a pitman connection, the combination with a pump rod or pitman, of a bushing formed of two like parts embracing said rod or pitman, a bolt for securing said bushing on said rod, a pair of plates on opposite sides of said bushing and secured thereto by said bolt, each of said plates having an outwardly inclined portion above the bushing terminating in a straight portion parallel to the axis of the rod, and means at the end of said plates for connecting them to a crank mechanism.
4. A pitman connection comprising a pitman, two similar plates each having an intermediate outwardly inclined portion and straight ends in parallel relation offset from

each other, a two-part bushing embracing said pitman having straight parallel sides against which the ends of said plates which are closer together are placed, a through bolt securing said ends to the bushing and pitman and a removable pin extending through openings in the wider ends of said plates for connecting the same to an operating mechanism.

20
25
In testimony whereof I affix my signature in presence of two witnesses.

FRED H. BARNEY.
